CALKING AND GLAZING GUN

Marshall M. Carson, Norman, Okla.

Application June 11, 1931. Serial No. 543,728

2 Claims. (Cl. 18—3.5)

This invention relates to a calking and glazing gun and has for its object to provide, in a manner as hereinafter set forth, a gun of such class so constructed and arranged for expeditiously and satisfactorily calking and glazing by air pressure stored within the device, and further to overcome the use and inconvenience caused by the carrying, dragging or tangling of a hose attached to and now generally employed for supplying air pressure to devices of the class to which the applicant's invention belongs.

A further object of the invention is to provide, in a manner as hereinafter set forth, a glazing and calking gun having means for automatically discontinuing the operation thereof when exhausted of the material which is to be expelled therefrom.

A further object of the invention is to provide, in a manner as hereinafter set forth, a calking and glazing gun having means for regulating the flow of the material expelled therefrom, as well as further providing for uniform flow of the material being expelled.

A further object of the invention is to provide, in a manner as hereinafter set forth, a calking and glazing gun with means for eliminating popping and escaping air at the outlet end of the gun during the operation of the latter and which results in an even flow of the material which is being expelled from the gun during the calking and glazing operation.

Further objects of the invention are to provide, in a manner as hereinafter set forth, a calking and glazing gun which is simple in its construction and arrangement, strong, durable, compact, thoroughly efficient in its use, conveniently operated, readily assembled, and inexpensive to manufacture.

With the foregoing and other objects in view, the invention consists of the novel construction, combination and arrangement of parts as hereinafter more specifically described, and illustrated in the accompanying drawing, wherein is shown an embodiment of the invention, but it is to be understood that changes, variations and modifications can be resorted to which fall within the scope of the invention as claimed.

In the drawing wherein like reference characters denote corresponding parts throughout the several views:—

Figure 1 is a vertical sectional view of a calking and glazing gun in accordance with this invention.

Figure 2 is a perspective view of the feed pipe.

Figure 3 is a perspective view of one of the sections of the expelling piston rest.

Figure 4 is a fragmentary view in top plan.

Referring to the drawing, the gun includes a barrel formed of a cylindrical body part 1 having a removable head 2 at one end and a fixed head 3 at its other end. The body part 1 at one end is formed with peripheral threads 4. The head 2 consists of a cylindrical part 5, a tapered part 6 and a contracted part 7. The part 5 has internal threads 8 which engage with the threads 4 for detachably securing the head 2 to the body part 1. The part 7 of head 2 is of materially less width than the part 5. The part 6 is interposed between the parts 5 and 7. The outer end 65 of part 7 is beveled downwardly from its front wall to its rear wall to provide the latter of less height than the former, or in other words the part 7 has its outer end inclined downwardly throughout from front to rear. The head 3 has an axial opening 9 and registering therewith is a sleeve 10 arranged within the body part 1 and formed with a valve seat 11 for an outlet valve 12. The stem 13 extends through sleeve 10 and has the valve 12 fixed thereto intermediate the 70 ends thereof. Guide means 14 are arranged within sleeve 10 for a portion of the stem 13. A guide means 15 is also arranged within the sleeve 10 at the inner end thereof for stem 13. Interposed between the guide means 15 and the 75 valve 12 and surrounding the stem 13 is a controlling spring 16 for valve 12 which normally acts to maintain valve 12 against the seat 11. The stem 13 projects from the inner end of sleeve 10 and is formed with an eye 17.

The body part 1 has secured therein intermediate the ends thereof a piston rest 18 formed of two abutting sections and of annular form. Holdfast means 19 extend through body part 1 and into rest 18 for fixedly securing it against the inner face of body part 1. The rest 18 divides body part 1 into an air chamber 20 and a combined material receiving and piston chamber 21. The chamber 20 is arranged below rest 18 and the chamber 21 above the latter. Carried by the 80 body part 1 is a normally closed air inlet valve device 22 adapted to be connected to a source of compressed air supply to provide for the supplying of compressed air to the chamber 20. The air pressure contained in the gun will be from 85 seventy-five to one hundred pounds per square inch.

Operating within the chamber 21 is a piston 23 provided with a packing 24 which rides against the inner face of body part 1. Adjustably con-

connected with the piston 23 is an eye bolt 25 carrying a flexible member or chain 26 which is attached to the eye 17 of the stem 13. The member 26 functions to open the outlet valve when the piston 23 has moved to an extent towards the head 2 to expel the material, that is all of the material from the chamber 21.

Secured to the body part 1 and projecting laterally therefrom is a supporting bracket 27 having connected thereto a grooved handle member 28 which inclines outwardly from the body part 1. The handle member 28 is also coupled to the body part 1 by an angle shaped coupling strap 29 which has one terminal thereof secured to body part 1 and its other terminal secured to the lower portion of handle member 28.

Fixedly secured to the end 8 of part 7 of the head 2 and disposed at an upwardly inclination from rear to front is a feeder pipe 30 having peripheral threads 31 at one end thereof and formed intermediate its ends with an oval shaped opening 32 in its lower portion providing a restricted outlet for the chamber 21. The pipe 30 projects laterally in both directions from the tip 7 of head 2 and has detachably connected to the threaded ends thereof a tip 33 of the desired length. The tip 33 has a beveled outer end 34. Slidably mounted on the pipe 30 is an adjustable tensioning member 35. The adjusting means for the member 35 consists of a screw 36 extending through and threadedly engaging with a lug 37 on pipe 30. The screw 36 engages in a socket 38 formed in the tensioning member 35. Projecting from the top of the pipe 30, in proximity to its other end is an apertured lug 39 which constitutes a stop for a purpose to be presently referred to.

Slidably mounted in the pipe 30 is a tubular trigger 40 having a beveled inner end 41. The trigger 40 projects from the rear end of the pipe 30 and is formed with a peripheral shoulder 42 adapted to abut against the edge at the lower end of pipe 30 to arrest the shifting movement of the trigger towards pipe 30. The outer end of trigger 40 is closed, as indicated at 42 and carries a depending finger piece 43. Attached to each side of the outer end 42 of the trigger 40 is a controlling spring 43 therefor and the said springs 43 have their upper ends attached to the tensioning member 35. The length of the trigger 40 is such that it will normally extend across and close the opening 32 and pipe 30 to the barrel. The springs 43 function to maintain the trigger in position thus referred to. Carried by the trigger 40 and extending through the lug 39 is a trigger guide bar 44 carrying an abutment nut 45 coacting with the lug 39 for limiting the outward pull of trigger 40. The nut 45 adjustably engages with the bar 44 to control in connection with lug 39 the extent of the outward pull of the trigger to vary the size of opening 30 for controlling the flow of the material to be expelled from the barrel and also to provide for a uniform flow. The lug 39 in connection with the bar 44 prevents the rotative movement of the trigger relative to the feeder pipe.

After the material has been supplied to the chamber 21 and with the piston 23 seated on the rest 18 the necessary amount of air pressure is

supplied to the chamber 20. By pulling the trigger away from the pipe 30 to open the gun to the latter, the air pressure will permit of acting to shift the piston in a direction to expel the material from the body part 1, through the opening 32, into the pipe 30 and out through the tip 33 to the point of utilization. The expelling action will be arrested when the piston 23 moves to an extent to have member 26 shift the valve 12 to open position.

The controlling springs 43 are adjusted by the screw 36, acting on the member 35 to shift the same forwardly on the pipe 30 or due to the action of the springs moving the member 35 towards the screw 36.

As the pipe 30 is provided with means for detachably securing the tip in position, it is obvious that various lengths of tips can be employed or coupled in position with respect to pipe 30. The grooved handle 28 enables the device to be gripped by the operator in a satisfactory manner to prevent slipping from the hand of the operator, due to the fact that the operator's fingers will seat in the grooved portion of the member 28.

What I claim is:

1. In a calking and glazing gun, the combination of a barrel from which the material to be used is expelled, a head for one end of the barrel and formed with a hollow contracted part providing an outlet for the barrel, the outer end of said part inclining downwardly from front to rear, an inclined nozzle feeder pipe secured intermediate its ends to the top of and formed with an intake permanently communicating with said part, a shiftable tubular trigger slidably mounted in and extending rearwardly from said pipe, said trigger having a lengthwise portion of its lower face extending across said intake for normally closing the intake, an adjustable tensioning member mounted on the pipe, controlling springs attached to said member and to the rear end of the trigger, said barrel and trigger having coacting parts providing a combined stop and guide means for the trigger for controlling the extent of the outward pull of the latter and to prevent rotative movement of the trigger relative to the pipe, and said means including a pair of parts, one adjustable relative to the other for varying the extent of the rearward pull of the trigger.

2. In a calking and glazing gun of that type including a barrel from which the material to be used is expelled and with the barrel having an outlet, the combination of a nozzle feed pipe extending across and having an intake opening intermediate its ends registering with said outlet, a bodily shiftable tubular trigger slidably mounted in and extending rearwardly from said barrel, said trigger normally closing said intake and having its rear end closed, a tensioning member carried by said pipe, a pair of lugs extended from the pipe, adjusting means for said member threadedly engaging in one of said lugs, controlling springs attached to said member and the rear portion of the trigger, and a forwardly extending guide carried by the trigger and slidably extending through the other of said lugs and provided with an abutment for arresting the rearward pull of the trigger.

MARSHALL M. CARSON.
